TOY GIRL FIGURE

Don A. Winton, Pasadena, Calif., assignor to J. L. Prescott Company, Passaic, N.J., a corporation of New Jersey

Filed July 22, 1969, Ser. No. 18,313

Term of patent 14 years

Int. Cl. D21—02

U.S. Cl. D34—4

FIG. 1

FIG. 2

FIG. 3

FIG. 4

FIG. 1 is a front elevation of a toy girl figure showing my new design;

FIG. 2 is a rear view;

FIG. 3 is a side elevation view of FIG. 1; and
FIG. 4 is a side view opposite to that of FIG. 3.

I claim:

The ornamental design for a toy girl figure, as shown.
